UNITED STATES PATENT OFFICE

170,944

DRINKING GLASS

Jack W. Robbins, Chicago, Ill.

Application March 14, 1952, Serial No. 18,884

Term of patent 14 years

(CL. D36—8)

To all whom it may concern:

Be it known that I, Jack W. Robbins, a citizen of the United States of America and resident of Chicago, county of Cook, State of Illinois, have invented a new, original, and ornamental Design for a Drinking Glass, of which the following is a specification, reference being had to the accompanying drawing, forming a part thereof, wherein:

Fig. 1 is a front elevational view of a drinking glass showing my new design;

Fig. 2 is a side elevational thereof. The lining is for shading. The essential features of my design reside in those portions shown in full lines.

I claim:

The ornamental design for a drinking glass, substantially as shown and described.

JACK W. ROBBINS.
